TRANSISTORIZED POWER SUPPLY UNIT

Bernard J. Bisnett, 15920 Rochin Terrace, Los Gatos,
Calif., and Bunny L. Wong, 442 Ocie Way, Hayward,
Calif.

Filed Mar. 4, 1964, Ser. No. 78,874

Term of patent 14 years

(Cl. D26—15)

1

FIG - 2

FIG - 3

FIG - 4

Fig- 5Fig- 6Fig- 7FIG. 1 is a front, top and right end perspective view of a transistorized power supply unit, showing our new design;

FIG. 2 is a left hand elevational view;

FIG. 3 is a right end elevational view;

FIG. 4 is a top plan view;

FIG. 5 is a front elevational view;

FIG. 6 is a rear elevational view; and

FIG. 7 is a bottom plan view thereof.

We claim:

The ornamental design for a transistorized power supply unit, as shown.
